HAND TOOL

Filed May 17, 1927

UNITED STATES PATENT OFFICE

OTTO ALTBACH, OF LOS ANGELES, CALIFORNIA

HAND TOOL

Application filed May 17, 1927. Serial No. 192,028.

This invention relates to a hand tool, and especially to a compound tool that can conveniently be carried about in the pocket.

It is one of the objects of my invention to 5 provide a compact and convenient tool that serves a number of purposes, such as a screwdriver and a knife.

It is another object of my invention to provide a double-ended tool, each end forming 10 a distinct implement, in conjunction with a convenient handle means for either of these ends.

It is still another object of my invention to provide a novel and compact electrician's 15 compound tool, in which the handle member for the tool when using one of the implements, is completely insulated, as by hard rubber or bakelite, from the operative end of the tool.

20 My invention possesses many other advantages, and has other objects which may be made more easily apparent from a consideration of several embodiments of my invention. For this purpose I have shown a few forms in 25 the drawings accompanying and forming part of the present specification. I shall now proceed to describe these forms in detail, which illustrate the general principles of my invention; but it is to be understood that this 30 detailed description is not to be taken in a limiting sense, since the scope of my invention is best defined by the appended claim.

Referring to the drawings:

Fig. 1 is a perspective view, partly broken 35 away, of a closed compound tool embodying my invention;

Fig. 2 is a fragmentary longitudinal sectional view, of the tool shown in Fig. 1;

Fig. 3 is a fragmentary top plan view, 40 taken in the direction of arrow 3 in Fig. 2, but with a portion of the insulation covering removed;

Fig. 4 is a fragmentary elevation of a slightly modified form of my invention; and

Fig. 5 is a fragmentary sectional view 45 thereof.

In general, my compound tool consists of a metal shank 11 that is shown in this instance as square, from one end of which extends a knife blade 12, and from the other

end, a screwdriver blade 13. It is obvious however that other kinds of tools could be substituted in place of the cutting implement and screw-driver herein shown.

I provide a casing or box for the implements. This casing is so arranged that a part can at will be removed to expose one of the tool extensions, the other part of the casing then serving not only to cover the other tool, but also as a handle. For this purpose I preferably provide a pair of metallic cylindrical interfitting sections 14 and 15. Each of these sections has a square counterbore, such as 16 and 17, which fits snugly over shank 11 and provides a shoulder against which the end of the shank 11 abuts, as clearly shown in Fig. 2. When either of these sections is removed, the other section serves as a handle for the exposed tool. In order to permit its use by electricians in connection with live conductors, the sections 14 and 15 are overlaid with a thick layer of insulation, indicated by 18 and 19.

In order to safeguard against inadvertent removal of the casing sections 14 and 15 when they are closed or when they serve as handles, I preferably provide a spring snap arrangement for locking them in place. Thus shank 11 can be provided with apertures 20 and 21 in which are located the spring-pressed buttons 22 and 23. These buttons or latches, being urged by springs 32 and 33 in an outward direction, engage in slots 26 and 27 in casings 15 and 14 respectively. That edge 24 or 25 of the slot nearest the end of its respective casing is engaged by the button, as shown most clearly in Fig. 2, whereby withdrawal of the casing is prevented until that button is depressed out of its cooperating slot. It is thus evident that these buttons in the position shown, retain the casing sections against axial movement. To depress these buttons below the cooperating shoulders, when it is desired to remove the casings, I provide insulation push-buttons 28 and 29 extending through apertures in the insulation casings 18 and 19, and retained on the end of a flat spring member 30 or 31 fastened to the casings below the insulation. These push-buttons are thus through the heads of spring 32

members 30 and 31 in contact with the tops of spring-pressed buttons 22 and 23 whereby these buttons 22 and 23 can be depressed. Coiled springs 32, 33 for urging buttons 22, 23 outwardly are anchored in any appropriate fashion at their inner ends in apertures 20, 21; and at their outer ends, to the buttons 22, 23.

The tool just described is adaptable for use by electricians, its handle being completely insulated. However, my invention can be applied to ordinary pocket implements, or such as are adapted to be suspended on a watch chain. Figs. 4 and 5 show such a form, in which casing sections 34, 35 can be left uncovered. One casing such as 34, can be provided at its end with a chain ring 36 to permit its being hung on a watch chain. The casing sections 34 and 35 can each be provided with a groove such as 37 for the accommodation, of a flat spring 38 carrying push-button 39 for depressing the locking button 40. In other respects this form is quite similar to that shown in Figs. 1, 2, and 3.

25 I claim:

In a hand tool, a shank having tool extensions at each end, a pair of cylindrical casing sections enclosing said extensions and meeting at the shank to form a closed box-like enclosure, an insulation covering for each section, a spring lock located in the shank for each section, and a releasing insulated button for each section operable outside the insulation covering for permitting the section to be removed, and whereby the other section can serve as an insulated handle for operating the exposed tool.

In testimony whereof I have hereunto set my hand.
